(57) **CLAIM**

The ornamental design for a LED light, as shown and described.

DESCRIPTION

FIG. 1 is a front, left and bottom perspective view of a LED light, showing my new design.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a bottom plan view thereof.

FIG. 7 is a top plan view thereof; and,

FIG. 8 is a partial enlarged view of the area labeled 8 in FIG. 1.
The dot-dash broken lines in FIGS. 1 and 8 are demarcating enlarged areas and form no part of the claimed design.
